Patented May 3, 1921.

*Inventor:
Ernest H. Strauss
per Frank A. Freark Attorney.*

UNITED STATES PATENT OFFICE.

ERNEST H. STRAUSS, OF CHICAGO, ILLINOIS.

DESIGN FOR A LAMP-SHADE.

57,793.

Specification for Design.

Patented May 3, 1921.

Application filed March 25, 1920. Serial No. 368,742. Term of patent 7 years.

To all whom it may concern:

Be it known that I, ERNEST H. STRAUSS, a citizen of the United States of America, residing at Chicago, in the county of Cook and State of Illinois, have invented a new, original, and ornamental Design for Lamp-Shades, of which the following is a specification, reference being had to the accompanying drawing, which forms a part thereof.

The figure is an elevation of a lamp-shade showing my new design.

I claim:

The ornamental design for a lamp-shade as shown.

ERNEST H. STRAUSS.
